UNITED STATES PATENT OFFICE.

SETH J. BUCKLAND, OF SPRINGFIELD, MASSACHUSETTS.

AUTOMATIC CHECK DEVICE FOR TROLLEY-CORDS.

SPECIFICATION forming part of Letters Patent No. 752,374, dated February 16, 1904.

Application filed April 22, 1903. Serial No. 153,769. (No model.)

To all whom it may concern:

Be it known that I, SETH J. BUCKLAND, a citizen of the United States of America, and a resident of Springfield, in the county of Hampden and State of Massachusetts, have invented 5 certain new and useful Improvements in Automatic Check Devices for Trolley-Cords, of which the following is a full, clear, and exact description.

10 This invention relates to an improved check or restraining device for the cord for the trolley-arm of an electric railway-car automatically operative upon the displacement of the trolley-wheel from its running engagement 15 along the trolley-wire, whereby the arm would under the reaction of the heavy spring thereof swing upwardly above the wire to restrain a trolley-arm from having any considerable extent of upward-swinging movement.

20 The object of the present invention is to provide a restraining or check device of the class indicated which is unusually simple in construction, involving a minimum of parts, and which is unusually efficient and quick in its 25 automatic action, the novel device being, however, non-effective under ordinary conditions and when the cord has a comparatively slow or gradual winding or unwinding relatively to the reel therefor, as incidental to changes 30 in grade of the trackway or of the level of the trolley-wire or as occasioned when the trolley-arm is controlled and guided by manipulation of the cord to bring it to its running engagement against the wire to check or restrain the rotational movements of the cord-reel, as of course is necessary under ordinary 35 and proper conditions.

40 The invention consists in a trolley-cord-restraining device comprising a suitable case, a winding-reel therein, a winding-spring reactive 45 in relation to the reel, a tooth-provided member provided to the reel, and a peculiarly-arranged pawl normally passive as to its effect for engagement with the teeth of the reel, but operative to quickly engage the teeth of the reel and to obstruct any considerable rotational movement of the reel when a rapid 50 rotating stress is developed in the reel, as would be occasioned by the disengagement of the trolley from the wire, resulting in a quick

unwinding strain being imparted to the trolley-cord, and in certain further parts and features, all substantially as hereinafter fully described, and set forth in the claims.

The improved device is illustrated in the accompanying drawings, in which—

Figure 1 is in part a rear elevation at the back side of the case and in part an elevation of the reel having the toothed flange and the pawl, as apparent by the breaking out of a portion of the rear wall of the case. Fig. 2 is a section as taken on the line 2-2, Fig. 1. Fig. 3 is a view of portions shown in the lower part of Fig. 1, the escapement or check pawl being shown in its reel-stopping engagement, which it would assume as due to a quick rotational movement of the tooth-flange reel occasioned by a sudden and rapid unwinding draft on the cord.

In the drawings, A represents the circular 70 casing in which the reel and devices coacting therewith are inclosed, said casing having at its back a the rigid metallic strap B, by means of which to engage and support the case with and upon the lug C, provided on the face of 75 the fender of the car, the spring-snap D detachably locking the parts, as indicated in Fig. 2. The back of the case has the internal circular boss b and the integrally-formed central stud d, on the neck-down forward end 80 portion d' of which the central circularly-apertured portion f of the cup-shaped reel G has bearing for rotation, while the annular cylindrical portion g of the reel toward the back of the casing has also bearing for rotation on the boss b, said reel portion g having the outwardly-extending flange h, provided with regularly-spaced teeth i i at comparatively long intervals. The reel has the thin metallic separated cheeks j j, and has there- 90 within the clock-spring H, one end of which is anchored and the other has attachment to the reel for producing in a manner common in this class of devices a winding-up stress on the reel.

J represents the trolley-cord in winding engagement around the barrel portion g of the reel and running off therefrom through an opening therefor, (indicated at h' in the upper portion of the casing.)

95

100

L represents the pawl, the same, as shown, comprising the members *m* and *n*, which are arranged obtuse angular to each other, and the pawl is intermediately pivoted at *o* just inside the back wall of the casing for an oscillatory movement in a plane of revolution of the ratchet-like teeth *i*. The fronts or engagement portions 10 of the teeth *i* are quite acutely angular to the backs 12, which latter 10 recede to the least marginally-prominent portions 13 between the teeth, with curves or inclinations about as shown. The distance between the two ends of the pawl is a little less than the distance between engagement edges 15 10 of two of the teeth *i*.

A spring *t*, having a comparatively low reactive power, is provided within the case and has an engagement with the pawl to normally maintain the checking member *m* thereof, as 20 seen in Fig. 1, out of the path of revolution of the teeth *i*, and consequently normally maintaining what may be considered the actuating member *n* of the pawl in its position inclined across such path. The comparatively 25 low degree of reactive power of the spring *t* is such as in practice to insure a timing of the successive outward motions of the pawl relatively to the ordinary oscillatory motion of the reel incidental to and occasioned by undulations in the trolley-wire.

The central stud *d* is surrounded by a sleeve 20, to which the inner end of the spring *H* is secured, the end face of which sleeve, next to the back *b* of the casing, is constructed with 35 a plurality of recesses 22, each having one boundary steep or perpendicular to the end face, while the other boundary is beveled, constituting, in substance, a ratchet-toothed end face to the sleeve, with which engages the 40 spring-pressed stud 23, fitted in a suitable socket therefor in the back wall of the casing.

The ordinary rotative force or reaction exerted on or through the medium of the spiral spring *H* is such as to keep a steep side of 45 the tooth against the stud, securing the anchorage of the inner end of the spring to all intents and purposes the same as if it were secured to the axis-stud; but this arrangement constitutes a provision whereby any un- 50 due turning in the wrong direction of the reel so that it would cause an unwinding of the spring will be against no resistance at the inner end of the spring, for the reason that the sleeve to which the inner end of the spring is 55 engaged will "back around," clicking over the end of the stud 23.

Assuming that the reel has imparted thereto a comparatively slow rotational movement in the direction of the arrow *x*, Fig. 1, as occasioned by the outward drawing of the trolley-cord as carried by the trolley-arm, which, for instance, may be swinging toward a rising portion of the trolley-wire under the powerful impetus of the trolley-arm spring, the 65 backs 12 of the teeth *i* will act cam-like

against the actuating-arm *n* of the pawl, resulting in throwing the checking-arm *m* of the pawl across the path of the teeth before the next rearward tooth reaches the end of such pawl-arm *m*, and it will be understood 70 that now there is a little intervening space between the left-hand end of pawl-arm *m* and the face 10 of the adjacent oncoming tooth *i* and that before the gradually-approaching teeth can come to where the end of the pawl-arm *m* was the spring *t* will have reswung such arm out of the tooth's path, and thus several of the teeth *i* may ride by the pawl, which incidentally is oscillated, without any 75 checking effect, however; but on another assumption that the trolley becomes disengaged from its wire and the trolley-arm upswinging causes a very sudden and quick rotary motion of the reel in the direction of the arrow *x* the nearest pawl-tooth to the leftward of 80 the pawl-actuating arm *n* on reaching the latter will more or less violently throw the pawl to the position shown in Fig. 3 and the rapidly oncoming next rearward tooth *i* will be brought by its engagement edge 10 against 85 the intercepting end of the working arm *n* of the pawl, the "lazy-spring" *t* being under such conditions as now considered too slow in its action to throw the pawl-arm *m* outside of the path of the tooth before the swiftly-moving 90 tooth reaches engagement therewith. Of course it is clear that any downward drawing on the trolley-cord whereby the latter will be automatically wound up by the reel, which in this instance would have its rotation the reverse of the direction of the arrow *x*, is a matter requiring no consideration, for the relations of the pawl and ratchet-like teeth *i* are such that this reversed rotation of the reel will occasion merely a clicking of its teeth 95 past the pawl, the latter incidentally vibrating.

A provision of considerable practicability for coaction with the pawl consists in providing a substantial shoulder or abutment *u* on the inner wall of the case adjacent the free end of the actuating-arm *n* of the pawl, against which such end may jam when the opposite end of the pawl is forcibly contacted against by one of the reel-teeth *i*, as shown in Fig. 3, this abutment-shoulder serving to relieve the pivot 110 *o* from becoming bent, strained, or otherwise effected in a manner to interfere with the delicacy of operation of the pawl.

Tests of this checking device have demonstrated that the trolley disengaged from the 115 wire can have only an upswing of from two to four inches before the trolley-arm will be automatically checked.

Having thus described my invention, what I claim, and desire to secure by Letters Patent, is—

1. In a trolley-cord-restraining device, the combination with the casing having the trolley-cord-winding spring-reel, rotatable therewith, said reel having a flange provided with a 130

series of regularly-spaced ratchet-like teeth, of a pawl pivotally mounted at an intermediate portion thereof on a suitable part of the casing comprising the actuating-arm *n* and the checking-arm *m*, the distance between the extremities of which are less than the distance between the engagement edges of two of the teeth, said casing having the abutment-shoulder *u* adjacent the free end of the pawl-actuating arm, and against which said end may contact, and a spring of low reactive power operative on the pawl to normally maintain the checking-arm thereof outside of the path of revolution of the reel-teeth.

15 2. In a trolley-cord-restraining device, the combination with the casing having an axial stud and having a spring-stud penetrating the

back of the casing adjacent the junction therewith of said axial stud, of the winding-reel, a sleeve surrounding said axial stud and having in its end face adjacent the back of the casing, the plurality of ratchet-teeth in which said spring-pressed stud engages, and the winding-spring *H* disposed within the reel and having one end connected thereto and its other end engaged with said sleeve, substantially as and for the purpose explained.

Signed by me at Springfield, Massachusetts, in presence of two subscribing witnesses.

SETH J. BUCKLAND.
